UNITED STATES PATENT OFFICE.

JAMES DWYER AND JOHN H. LANE, OF DETROIT, MICHIGAN.

DESIGN FOR A MAGAZINE-SECTION FOR STOVES.

SPECIFICATION forming part of Design No. 31,247, dated July 18, 1899.

Application filed June 19, 1899. Serial No. 721,146. Term of patent 14 years.

To all whom it may concern:

Be it known that we, JAMES DWYER and JOHN H. LANE, citizens of the United States, residing at Detroit, in the county of Wayne and State of Michigan, have invented and produced a new and original Design for Magazine-Sections for Stoves, of which the following is a specification, reference being had therein to the accompanying drawings, in which—

10 Figure 1 is a perspective view, and Fig. 2 is a side elevation.

The device as a whole has the appearance of a rounded spout or tubular member A, passing at an acute angle through a plate B. 15 The top a and base b of the member A lie in parallel planes, to which the longitudinal axis of said member is inclined. The lower section c of the member A is slightly curved longitudinally and tapers from an elongated

cross-section at its intersection with the plate 20 B to a substantially circular cross-section at the base. The plate B is slightly curved in cross-section and of an arch-shaped contour.

The leading feature of the design consists in the appearance of the rounded tubular member A, passing at an acute angle through the plate B. 25

What we claim as our invention is—

The design for magazine-sections of stoves, substantially as herein shown and described. 30

In testimony whereof we affix our signatures in presence of two witnesses.

JAMES DWYER.
JOHN H. LANE.
